UNITED STATES PATENT OFFICE.

WILLIAM P. CAINE, OF ENSLEY, ALABAMA.

METHOD AND APPARATUS FOR THE GENERATION AND UTILIZATION OF STEAM IN AN INCLOSED CYCLE.

Application filed October 19, 1921. Serial No. 508,744.

This invention relates to apparatus for the generation and use of steam in power plants wherein the steam is kept in an inclosed cycle, the exhaust steam from the prime mover being separated from the water of condensation, then superheated and passed or drawn into a regenerator by jets of superheated high pressure steam with which it unites, forming a working pressure which is the equalization of the two pressures and is used to drive the prime mover.

This apparatus contemplates that the only water to be evaporated is the cold water required to replace the weight of steam and water leaking out of the system and the amount condensed by radiation and work losses. As this is much less than in steam plants where the exhaust is delivered either to the atmosphere or to a condenser, a greater amount of the heat in the fuel will be delivered in the form of actual work by reason of the greatly reduced latent heat loss.

The only driven unit auxiliary to the prime mover is the feed pump and that is small in comparison with that used in the present day plants, as it is only required to pump back the condensation and the fresh leakage replacement water.

The type of steam plant herein described makes it desirable that the prime mover be placed close to the steam generator; thereby keeping the heat loss by radiation down to the minimum amount.

My invention is typically illustrated in the accompanying drawings, in which:—

Fig. 1 is a vertical cross sectional view taken through a boiler plant and regenerator, the prime mover, tubing and piping being shown in elevation.

Fig. 2 is an enlarged cross sectional view of the regenerator.

Fig. 3 is a detail cross-sectional view of a typical air separator.

Similar reference numerals refer to similar parts throughout the drawings.

In the particular design of plant illustrated in my drawings, the steam generator apparatus is divided into three distinct sections, namely: the high pressure steam generating section comprising the boiler 1; the high pressure steam super-heating section, comprising the superheater 2; and the exhaust steam section comprising the water separator 18, which supplies the condensed

water to the high pressure boiler supply pump, and the exhaust steam superheater 5.

This condensed water from the separator 18 will flow by pipe 6 to the boiler feed pump 7, such additional water as is needed to replace the leakage from the system being introduced through the pipe 6^a from any desired source. Both pipes 6 and 6^a may supply cold or hot water as desired, and from the pump 7 the water flows to the high pressure boiler 1 wherein its evaporated by the heat from the furnace 9 and is delivered as high pressure steam through pipe 10 to the superheating coils 2 in the furnace. From the superheater the high pressure dry steam flows through pipe 11 to the nozzle 12 in the chamber 13 of the regenerator 3. The exhaust steam will pass through the superheating tubes 5 into a collecting chamber 14 and from there it flows to the regenerator through a pipe 15, entering the side of the regenerator chamber 13.

The regenerator 3 is an ejector in which the high pressure superheated steam passing through its nozzle 12 will draw in the superheated exhaust steam, the two equalizing in the combining tube 13^a and forming steam at an intermediate pressure which I

regard as the working pressure, as the steam is at this working pressure when delivered to the prime mover 4 through pipe 17. All of the exhaust steam from the prime mover

flows to the separating chamber 18 of the exhaust superheater through a pipe 19, thus completing the cycle. The air is allowed to escape into the atmosphere by a suitable

means such as a vent in the separator 8 that should be large enough to eliminate all of the air and some of the exhaust steam will probably be lost at this place. A typical

showing of an air separator is shown in Fig. 3 where the small nozzle 8^a will permit a slight escape of steam entraining with it the air that is collected in the system, and it will be noted the air separator is connected with the system through pipe 6 which

enters at the water line in the separator drum 18 and is thus at the lowest point in the separator where the air, which is heavier than the vapor, would tend to collect. Obviously any suitable standard air valve or eliminating element may be used in place of the separator 8 as shown.

The condensed water will flow by pipe 6 to the boiler feed pump 7 and be pumped

thereby into the high pressure boiler fast enough to keep the water level in the chamber 18 below the exhaust steam inlet. The pressure used by the prime mover had best 5 not be above one half that of the high pressure steam so that the high pressure steam will flow out of the nozzle or nozzles 12 at its highest velocity and therefore will be capable of drawing in the maximum amount 10 of exhaust steam. It is desirable to control the high pressure steam flow to the regenerator and this I do automatically with a valve 20 in the supply line 11 having a diaphragm 21 actuated by the working pressure 15 supplied thereto by the pipe 22 tapped into the working pressure line 17.

There should also be an automatic pressure operated valve 23 in the superheated exhaust steam line 15 to the regenerator that 20 will close if the pressure approaches the maximum which the exhaust superheater is designed to carry. This valve 23 I operate by a diaphragm 24 exposed to the exhaust steam pressure beyond the valve 23 by the 25 steam line 25. It is probable that a steam turbine will be the best form of prime mover to be used, as it is not necessary to contaminate the steam with a lubricant and thus the exhaust steam would be practically 30 as clean as when it left the steam generator.

The steam thus works in an inclosed cycle, being first utilized at working pressure in a prime mover, then the water is separated from the exhaust steam which is then superheated, the condensed water is returned to the high pressure boiler, and the steam from that boiler is superheated and utilized to regenerate the superheated exhaust steam to form steam at a predetermined working pressure 40 which is delivered to the prime mover, thereby completing the circuit. By the elimination of air and the supply of replacement water, the volume of steam and water in the inclosed circuit is maintained substantially 45 constant.

Having thus described my invention, what I claim as new and desire to secure by Letters Patent, is:—

1. The herein-described method of generating and regenerating steam in an inclosed cycle, which consists in generating high pressure steam, separating the condensed water from the exhaust steam from a prime mover, returning such water to replace the water 50 evaporated to generate said high pressure steam, superheating the exhaust steam after the separation therefrom of the condensed water, regenerating the superheated exhaust steam by commingling it with high pressure steam, delivering the combined high and low pressure steam as the working fluid to said prime mover, and adding sufficient fresh water to the circulation to replace losses in the water volume in the system.

2. The herein-described method of generat-

ing and regenerating steam in an inclosed cycle, which consists in generating high pressure steam and superheating it, separating the condensed water from the exhaust steam from a prime mover and utilizing the water 70 to replace water evaporated to generate said high pressure steam, superheating the exhaust steam after the separation therefrom of the condensed water, regenerating the superheated exhaust steam by commingling 75 it with high pressure steam, delivering the combined high and low pressure steam as the working fluid directly to said prime mover, and adding sufficient fresh water to the circulation to replace losses in the water volume 80 in the system.

3. The herein-described method of generating and regenerating steam in an inclosed cycle, which consists in generating high pressure steam, separating the condensed water 85 from the exhaust steam from a prime mover and returning such water to replace water evaporated to generate said high pressure steam, superheating the exhaust steam and then regenerating it by commingling it with 90 high pressure steam, thereby producing a working fluid having an intermediate pressure, delivering this working fluid directly to said prime mover, adding sufficient fresh water to the circulation to replace losses in 95 the water volume in the system, and separating air from the circulating medium.

4. The herein-described method of generating and regenerating steam in an inclosed cycle, which consists in generating 100 high pressure steam, separating the condensed water from the exhaust steam from a prime mover, returning such water to replace water evaporated to generate said high pressure steam, superheating the exhaust steam and regenerating it by commingling it with high pressure steam, delivering the combined high and low pressure steam as working fluid having an intermediate pressure directly to said prime 110 mover, adding sufficient fresh water to the circulation to replace losses in the water volume in the system, separating air from the circulating medium, and automatically regulating the flow of high pressure and exhaust steam to said regenerator to maintain 115 a substantially uniform pressure in the working fluid.

5. In combination, a furnace, a prime mover, a high pressure steam boiler heated 120 by said furnace and adapted to supply live steam for the prime mover to a regenerator, a water separating chamber, a pipe for conducting the exhaust steam from said prime mover into said separating chamber, a superheater for the exhaust steam, a steam regenerator having pipes conducting the high pressure and superheated exhaust steam thereto, and a pipe to conduct the regenerated steam directly to the prime mover. 125

6. In combination, a furnace, a prime mover, a high pressure steam boiler heated by said furnace and adapted to supply live steam for the prime mover to a regenerator, 5 a superheater to which the high pressure steam is delivered, a pipe for conducting the exhaust steam from said prime mover, a water separating chamber into which said pipe delivers the exhaust steam, a super- 10 heater for the exhaust steam, a steam re- generator having pipes conducting the superheated high pressure and the super- heated exhaust steam thereto, and a pipe to conduct the regenerated steam directly 15 to the prime mover.
7. In combination, a furnace, a prime mover, a high pressure steam boiler heated by said furnace and adapted to supply live steam for the prime mover to a regenerator, 20 a superheater to which the high pressure steam is delivered, a pipe for conducting the exhaust steam from said prime mover, a water separating chamber into which said pipe delivers the exhaust steam, a super- 25 heater for the exhaust steam, a steam re- generator having pipes conducting the superheated high pressure and superheated exhaust steam thereto, a pipe to conduct the regenerated steam to the prime mover, and 30 means to draw off from the water separator air collecting in the inclosed system.
8. A steam power plant including an in- closed steam circulating system comprising
- a prime mover, a water separator adapted to receive the exhaust steam of said prime 35 mover, an exhaust steam superheater, a high pressure steam boiler, a return for the sepa- rated water to said boiler, a superheater for the high pressure steam, and a regenerator having means for the delivery of both the 40 superheated high pressure steam and the superheated exhaust steam thereto in pre- determined relative volumes to maintain the desired working pressure for the steam 45 flowing directly from the regenerator to the prime mover.
9. A steam power plant including an in- closed steam circulating system comprising 50 a prime mover, a water separator adapted to receive the exhaust steam of said prime mover, an exhaust steam superheater, a high pressure steam boiler, a return for the sepa- rated water to said boiler, a superheater for the high pressure steam, a regenerator hav- 55 ing means for the delivery of both the super- heated high pressure steam and superheated exhaust thereto in predetermined relative volumes to maintain the desired working pressure for the steam flowing directly from the regenerator to the prime mover, means to withdraw from the bottom of the water sepa- 60 rator the air tending to collect in the steam circulating system, and means to supply thereto water to replace leakage losses.

In testimony whereof I affix my signature.
WILLIAM P. CAINE.
